US0D1075282S

(12) United States Design Patent (10) Patent No.: US D1,075,282 S
(45) Date of Patent: * May 20, 2025

(54) OBJECT HOLDER

(71) Applicant: Lindsey Ferrell, Lakeland, TN (US)

(72) Inventor: Lindsey Ferrell, Lakeland, TN (US)

() Term: 15 Years

(21) Appl. No.: 29/804,369

(22) Filed: Aug. 19, 2021

(51) LOC (15) Cl. 24-04

(52) U.S. Cl.

USPC D24/193; D24/195

(58) Field of Classification Search

Assistant Examiner — Jane Yoon

(57) CLAIM

The ornamental design for an object holder, as shown and described.

DESCRIPTION

FIG. 1 is a top perspective view showing my new design for an object holder.

FIG. 2 is a bottom perspective view thereof.

FIG. 3 is a front view thereof.

FIG. 4 is a rear view thereof.

FIG. 5 is a bottom view thereof.

FIG. 6 is a top view thereof; and,

FIG. 7 is a left side view thereof, the right side being a mirror image thereof.

In the drawings, the broken lines depict environmental portions of the object holder, which form no part of the claimed design.

1 Claim, 6 Drawing Sheets
